UNITED STATES PATENT OFFICE.

ITHAMER A. ROBINSON, OF DE KALB, ILLINOIS, ASSIGNOR OF ONE-HALF
TO JOSEPH F. GLIDDEN, OF SAME PLACE.

KNIT FABRIC FOR THE MANUFACTURE OF MITTENS.

SPECIFICATION forming part of Letters Patent No. 244,933, dated July 26, 1881.

Application filed May 7, 1881. (No model.)

To all whom it may concern:

Be it known that I, ITHAMER A. ROBINSON, of De Kalb, in the county of De Kalb and State of Illinois, have invented a new and valuable Improvement in Knit Fabrics for the Manufacture of Mittens; and I do hereby declare that the following is a full, clear, and exact description of the construction of the same, reference being had to the annexed drawings, making a part of this specification, and to the letters and figures of reference marked thereon.

Figures 1 and 2 of the drawings are perspective views of my invention, and Fig. 3 is a cross-section of the same.

This invention has relation to the manufacture of mittens; and it consists in providing a knit tubular fabric having continuously connected in the knitting alternate short portions of closely-twisted yarn or thread for the wrist, and longer portions of more loosely-twisted yarn or thread for the hand-covering and lining, all as hereinafter more fully shown and described.

In the manufacture of mittens it is important, as far as possible, to dispense with seams; and the object of this invention is especially to avoid making seams along the side and at the end of the wrist, the lining being connected to the wrist portion in the manufacture of the fabric and turned in in the formation of the mitten, as hereinafter described.

The knitting is done on the ordinary circular machines, the yarns employed differing in size and density or closeness of twist. The tubular fabric may be commenced with a thin and loosely-twisted yarn suitable for lining the mitten, or the portion thereof next the wrist, and a sufficient length of this knitted for one mitten. The fabric is then continued by using a heavier and closely-twisted yarn to form the wrist portion *a*, and after this has been carried sufficiently far the fabric is continued by means of a yarn which is not so closely twisted as the wrist-yarn, and which is heavier than that used for the lining portions. This part *b* of the tube fabric is designed to form the outside covering or mitten proper, and it is continued for a sufficient distance or

length to form, when divided, two mittens. 50 At the end of the double-mitten portion *b* is formed, by using the closely-twisted yarn above mentioned, another wrist portion, *a*. After this, using a loose thin yarn, a lining portion, *c*, is knit of double length, the design being to 55 divide the lining portion, so that each section will serve for the mitten connected thereto.

It is apparent that yarns of different colors may be employed in making this fabric, when desirable.

The tubular fabric is continued as long as may be required, the succession of the mitten-wall portions *b*, wrist portions *a*, and lining portions *c* being regularly observed.

Instead of knitting double hand-lengths, as 65 indicated above, and double lengths for linings, there may be a variation, producing a fabric with single hand-lengths, succeeded by single wrist portions and single lining portions continuously; but this form of the fabric is not 70 so desirable, because it requires the yarn to be changed on the machine more frequently, and is therefore more expensive.

Mittens are formed from this fabric by turning the lining portion up inside the outer or 75 mitten portion to any desired position, and securing them together in any proper way.

In an application of the same date as this is shown and described an article which is made from the fabric described and claimed 80 herein.

Having described this invention, what I claim, and desire to secure by Letters Patent, is—

A continuous knit tubular fabric for the manufacture of mittens, consisting of lining portions *c*, wrist portions *a*, and outer or mitten portions, *b*, each portion succeeding the other in regular order in the knit fabric, and consisting of material of different textures, substantially as specified.

In testimony that I claim the above I have hereunto subscribed my name in the presence of two witnesses.

ITHAMER A. ROBINSON.

Witnesses:

JOHN M. ROBINSON,
FRED. C. HINMAN.
